UNITED STATES PATENT OFFICE.

POWHATAN ROBINSON, OF NEW YORK, N. Y., ASSIGNOR TO NEW YORK SPORTING GOODS COMPANY, OF NEW YORK, N. Y., A CORPORATION OF NEW YORK.

COMBINED TENT AND KNAPSACK.

1,198,773.

Specification of Letters Patent. Patented Sept. 19, 1916.

Application filed March 1, 1916. Serial No. 81,309.

To all whom it may concern:

Be it known that I, POWHATAN ROBINSON, a citizen of the United States of America, residing at New York city, county and State 5 of New York, have invented certain new and useful Improvements in Combined Tents and Knapsacks, of which the following is a full, clear, and exact description.

This invention relates to improvements in 10 camping tents, the object being to provide a tent that can be folded into a sack and arranged in the form of a knapsack so as to be conveniently carried by the camper.

My improved tent comprises a ground- 15 cloth having pockets and back or shoulder- straps applied thereto, the tent proper being secured to the said ground cloth and ar- ranged to be folded and completely en- 20 enveloped by the ground-cloth when packed for transportation. The back or shoulder- straps are provided for the purpose of hang- 25 ing the folded tent upon the back of the camper while hiking, the pockets being pro- vided to carry articles such as a camera-out- fit or other small articles such as combs, brushes, soap, towels, etc.

Further features of improvement will hereinafter appear.

I will now proceed to describe my inven- 30 tion in detail, the essential features of which will be summarized in the appended claims, reference being had to the accompanying drawings, forming part hereof, wherein—

Figure 1 is a perspective view of my im- 35 proved tent set up for use; Fig. 2 is an enlarged rear view thereof; Fig. 3 is an enlarged fragmentary vertical sectional view, the section being taken on a line 3—3 in Fig. 2; Fig. 4 is a similar view, the section 40 being taken on a line 4—4 in Fig. 1; Fig. 5 is a detail view of a detachable fly for cov- 45 ering the front opening of the tent; Fig. 6 is a plan view showing the ground-cloth spread out, being the first step in the oper- 50 ation of folding the tent to form the knapsack; Fig. 7 is a similar view illustrating the second step in the folding operation; Fig. 8 is a similar view illustrating the third step in the folding operation; Fig. 9 is a 55 plan view illustrating the fourth step in the folding operation; Fig. 10 is a cross sec- tional view of the back when folded but be- 60 fore being laced; Fig. 11 is a perspective view of the tent folded into knapsack form;

and Fig. 12 is a similar view of the front 55 of the folded tent or knapsack.

Referring to Fig. 6, it will be seen that my improved tent comprises a rectangular ground-cloth 1 having attached thereto a foldable angular shaped covering or tent 2, 60 the side edges of the ground cloth 1 being provided with peg-straps or ropes 3, and the sides 4 and 5 of the tent 2 having at- tached thereto stay-ropes 6.

As can be seen in Figs. 6 and 8, the ground 65 cloth 1 has secured to its under side two strips 7 and 8 having eyelets 10 and an apron 9, having eyelets 11, which serves to cover the adjacent ends of the halves of the folded pack, as will be hereinafter ex- 70 plained.

My improved tent is also provided with a sill 12 (Fig. 1) which can be turned up, to prevent water from entering the tent. The front strips 13 and 14 of the tent are pro- 75 vided with snap fasteners 14 (Fig. 1) to receive the buttons 16 carried by a detach- able fly 17 (Fig. 5). The fly 17 also carries a button 18 to engage a socket 19 carried by the sill 12.

The tent may be held erect by a ridge- 80 pole or by guy-ropes 20 and 21 each of which can be tied to a tree. The front opening in the tent is preferably covered by a net-like fabric 22 which can be raised or pushed 85 aside when a person wishes to enter or leave the tent.

My improved tent is also provided with a window 23 having a shade or covering 24 (Figs. 2 and 3), the said window being lo- 90 cated in the back 25 of the tent. The cover or shade 24 can be raised by means of draw- 95 ing strings 26 which pass through eyelets 27 over the top of the window, and the win- dows cover 24 can be lowered by means of drawing strings 28 which pass through eye- 100 lets 29 near the bottom of the window. The raising and lowering of the window can be accomplished from the inside of the tent. When the shade 24 is raised by pulling upon the strings 26, it will fold up in obvious manner.

The strips 7 and 8 are sewed or otherwise attached along their edges 30 to the ground- 105 cloth 1 and the apron 9 is secured along its edge 31 to the ground-cloth 1; hence the strips 7 and 8 and apron 9 are flaps (see Fig. 10). When the tent is folded, as shown

in Fig. 10, laces 32, (one only being shown in Fig. 12) are passed through the eyelets 10 and 11.

Adjacent one end of the ground-cloth 1, I 5 secure pockets 33 and 34 (Fig. 12) having flaps 35 and 36, respectively, to cover the open ends thereof. The pockets are provided with fastening straps 37 to secure the flaps 35 and 36. The pockets 33 and 34 are 10 provided for the purpose of carrying small articles. The ground-cloth 1 is also provided with shoulder straps 38 and 39 which are arranged to engage rings 40, hooks 41 being provided for the purpose. To carry 15 the folded tent or pack, the straps 38 and 39 are passed over the shoulders and fastened together by the clasps and hooks 40 and 41. When the tent is set up the shoulder-straps and pockets will be in contact 20 with the ground.

To fold the tent into a pack or knapsack, the ground-cloth will be spread upon the ground as shown in Fig. 6, and the tent proper folded thereon, the blankets, fly 17 25 and clothing being placed thereupon. The ground-cloth will then be folded longitudinally along its center and will appear as shown in Fig. 7, the tent, blankets, etc., being contained within the fold. The thus 30 folded ground cloth, tent, etc., will be again folded inwardly transversely along the lines 42 and 43, respectively. The thus folded structure will now appear as shown in Fig. 9. The next step will be to fold the structure, at the meeting edges, indicated by 44 35 in Fig. 9, that is to say, to bring the ends 45 and 46 together. The pack will now be complete, and it remains but to pass the laces 32 through the eyelets 10 and 11 of the 40 strips 7 and 8 and apron 9 to secure the folded sections together. After having applied the laces and secured them, the pack will appear as shown in Fig. 12. When the 45 last folding operation has been completed, the apron 9 will, before the laces 32 are applied, be folded over the ends 45 and 46 of the pack to cover the said ends. The pack will now be in condition to be strapped to the back.

Having now described my invention, what I claim and desire to secure by Letters Patent is:

1. The combination of a ground-cloth, a foldable covering secured thereto arranged 5 to be set up to form a tent open at one end, said ground-cloth being arranged to com-

pletely cover said tent when said tent and ground-cloth are folded into a pack and eyelets to receive a lace carried by said ground-cloth.

60

2. The combination of a ground-cloth, a foldable tent secured thereto, flaps carried by said ground-cloth and secured to the under side of said ground-cloth, said flaps extending throughout the greater part of 65 the length of said ground-cloth, and eyelets carried by said flaps, to receive a lace when said ground-cloth and tent are folded into a pack.

3. The combination of a ground-cloth, a 70 foldable tent secured thereto, flaps carried by said ground-cloth and secured to the under side of said ground-cloth, said flaps extending throughout the greater part of the length of said ground-cloth, eyelets carried by said 75 flaps, to receive a lace when said ground-cloth and tent are folded into a pack, an apron also carried by said ground-cloth arranged to be folded over to cover the ends of the folded over ground-cloth, and means 80 to secure said apron after it has been folded over to cover said ends.

4. A tent consisting of a ground-cloth, a foldable tent carried thereby, said ground-cloth being arranged to be folded longitudinally 85 thereof to envelop said tent, said folded ground-cloth and enveloped folded tent being adapted to be folded transversely to form a pack, an apron carried by said ground-cloth arranged to be folded over and 90 cover the adjacent ends of the folded pack, means to secure the folded portions of the pack and apron together, pockets carried by said ground-cloth, and means to secure the folded pack upon the back of a person. 95

5. The combination of a ground-cloth, a foldable covering secured thereto and arranged to be set up to form a tent, said ground-cloth being arranged to completely 100 cover the tent when it and the ground-cloth are folded into a pack, side-flaps extending from said ground-cloth and adapted to cover the adjacent sides of the folded pack, and means on said side-flaps to detachably secure the pack in the folded or packed condition.

Signed at New York city, N. Y., this 28 day of February, 1916.

POWHATAN ROBINSON.
